UNITED STATES PATENT OFFICE.

CHARLES CALVERT LAMB, OF CHICAGO, ILLINOIS, ASSIGNOR OF ONE-HALF TO
WILLARD M. McEWEN, OF CHICAGO, ILLINOIS.

RAIL-JOINT.

1,144,714.

Specification of Letters Patent. Patented June 29, 1915.

Application filed February 19, 1913, Serial No. 749,334. Renewed January 2, 1915. Serial No. 254.

To all whom it may concern:

Be it known that I, CHARLES CALVERT LAMB, a citizen of the United States, and a resident of Chicago, in the county of Cook and State of Illinois, have invented certain new and useful Improvements in Rail-Joints; and I do hereby declare that the following is a full, clear, and exact description thereof, reference being had to the accompanying drawings, and to the letters of reference marked thereon, which form a part of this specification.

This invention relates to rail joints of that kind consisting of a joint bar which rests on the ties and is adapted to support the meeting ends of the rails, and is provided with means by which the ends of the rails are secured thereto and held rigidly in alinement with each other, and it includes, as one feature thereof, improved features of construction in means for rigidly and securely holding the meeting ends of the rails in engagement with the joint bar, and as another feature thereof, means associated with the joint bar for holding the rail joint and rails from movement or displacement in a horizontal direction.

One of the objects of the invention is to provide in connection with a one-piece joint bar having longitudinal, side members extending at opposite sides of the rails, means operating with a wedge action for tightly and securely clamping the ends of the rails in engagement with the joint bar, and another object of the invention is to provide anchoring means separate from, or independent of, the ties, for preventing horizontal shifting of the rail joint, the rails and the ties, such as is liable to occur through the endwise movement of creeping of the track under the action of the passing trains on grades or inclines, or through the tendency to sidewise shifting of the rails under the action of passing trains on curved parts of the track.

The invention consists in the matters hereinafter described and pointed out in the appended claims.

In the accompanying drawings illustrating my invention—Figure 1 is a perspective view of a rail joint embodying my invention; Fig. 2 is a view of the joint, partially in elevation and partially in vertical section, taken upon line 2—2 of Fig. 4; Fig. 3 is a

horizontal section taken upon line 3—3 of Fig. 4; Fig. 4 is a transverse section of the joint, taken upon line 4—4 of Fig. 2; Fig. 5 is a cross sectional view of the joint, taken upon line 5—5 of Fig. 2; Fig. 6 is a side view of the anchor separate from other parts.

As shown in the accompanying drawings, the meeting ends of the track rails 5, 5 are supported and held in and by a one-piece joint bar, consisting of a horizontal base plate 6 and longitudinally extending side members 7 and 8, which rise from the base plate at opposite sides of the rail-ends. The base-plate 6 is adapted to rest on two adjacent ties 9 and 10, and is provided in its central part with a central, longitudinal, depending, stiffening web 11 having, at its lower margin, outwardly extending horizontal flanges 12, 12. The vertical web 11 and the stiffening flanges 12 are joined to each other and to the base plate by transverse, vertical webs 14, 15, 15, of which the web 14 is located midway between the ends of the web 11 and the flanges 15, 15 are located at the ends of the web and adjacent to the ties. The longitudinal web 11, the transverse webs 14, 15, and 15 and horizontal flanges 12, 12 are made integral with the base plate and together constitute a girder by which the base-plate is stiffened in its part between the ties to prevent downward flexure thereof under downward pressure of the car wheels on the meeting ends of the rails. Adjacent to its ends, exterior to the ties, the base plate 6 is provided with depending transverse webs 16, 16 and with central, longitudinally extending flange members 17, joining the same with the end portions of the base plate which extend beyond the said transverse webs 16, 16.

The longitudinal side members 7 and 8 of the joint bar are arranged to extend inwardly over the base flanges of the rail and then upwardly adjacent to, and parallel with, the webs of said rails, their upper margins being located adjacent to or in contact with the under surfaces of the rail-heads. The side member 7 is provided with a central, transverse flange 7^a and with transverse flanges 7^b, 7^b at its ends; said flanges being joined to the inwardly and upwardly extending parts of said side-piece, and acting to stiffen the same in a manner

to prevent flexure of said parts relatively to each other. The side member 8 is provided with like stiffening flanges 8^a and 8^b, 8^c.

In the case of one of the side members 7, 5 the inwardly and downwardly facing surfaces 7^c, 7^d thereof are shaped to conform to the adjacent outwardly and upwardly facing surfaces of the web and base flanges of the rails, and have bearing contact with 10 said surfaces when the rail-ends are in place in the joint bar. In the case of the other longitudinal member 8, the inwardly and downwardly facing surfaces 8^c, 8^d thereof are spaced from the adjacent surfaces of the 15 webs and base flanges of the rails and said inwardly and downwardly facing surfaces 8^c and 8^d are inclined from end to end of the side members, so as to leave tapered spaces between the said member 8 and the adjacent 20 surfaces of the base flanges and webs of the rails. Inserted between said member 8 and the ends of the rails is a wedge piece 18, which is made generally of L-shape in cross section and consists of a base member 18^a 25 and an upright member 18^b, which are made in one piece or integral with each other. Both the base member 18^a and the upright member 18^b of said wedge piece are tapered from end to end, the tapered form being given 30 to such parts by making their upwardly and outwardly facing surfaces inclined to correspond with the inclined downwardly and inwardly facing surfaces of the member 8. The said longitudinal side members 7 and 8 35 of the joint bar are made substantially shorter than the length of the bar itself and preferably only slightly longer than the distance between the ties on which the joint bar is supported. The wedge member 18 is 40 made slightly longer than the side member 8 engaged thereby and is provided at its thicker end with a transverse arm 19, which extends outwardly from the outer margin 45 of the base member 18^a over the top surface of the base plate and projects beyond the outer lateral margin of said base plate. By preference, the said arm 19 is made integral with the wedge member and is extended over the top of the base member 18^a inwardly to the upright member 18^b. The 50 lower surface of said arm 19, in its part exterior to the base member 18^a and the side margin of the base flange of the rail, is shaped to conform to and is adapted to rest 55 or bear against the marginal portion of the top surface of the base-plate. In the outer end of said arm is formed a spike hole 19^a. Said arm 19, thus arranged, is adapted to come over or above the tie 9 and when the 60 wedge member is inserted in place a spike, as indicated by 20, is inserted through the spike hole 19^a and driven into the tie so as to securely hold the wedge member from end- 65 wise movement. The spike thus driven through the arm 19 serves not only to hold

the wedge member from movement but also to aid in holding the joint bars to the ties. As shown in the drawings, three other spikes 21, 21, 21 are driven into the ties 9 and 10 with their heads engaged with the side margins of the end portions of the base plate.

As a means, additional to the wedge member, for securing the ends of the rails in the joint bar, track bolts 22, 22 are inserted horizontally through the side members 7 70 and 8, the upright member 18^b of the wedge piece and the webs of the rails. Said track bolts are provided with heads 22^a and nuts 22^b. When said nuts are tightened the upper margins of the side members 7 and 8 75 are drawn toward each other and against the rail webs and wedge piece; a slight inward movement of the side members being permitted through the yielding of said side members, due to elasticity of the metal. In other words, the track bolts serve to hold 80 said side members from spreading apart under the action of the wedge member after the latter is inserted in place. The bolt holes 7^c and 8^c, formed in the side members 90 7 and 8 for the insertion of the bolts, will be preferably slightly elongated longitudinally of said members, in order to permit the relative endwise movement of the rail ends under the expansion and contraction 95 of the rails due to changes in temperature. The bolt holes 5^a, 5^a, in the webs of the rails, will preferably be made circular, but only slightly larger in diameter than the track bolts. The upright member 18^b of the 100 wedge piece is provided with two bolt holes 18^c, 18^c, which are elongated longitudinally of the wedge member to such an extent as required to provide for the necessary end- 105 wise movement of the wedge member when driven into contact with the rail and joint bar.

In the assembling of the parts of a rail joint, embracing the features of construction described, the ends of the rails will be 110 inserted into the longitudinal slot or opening of the joint bar and brought into proper position relatively to each other, and the wedge member will then be driven tightly into place, so as to clamp the ends of the 115 rails rigidly and firmly between the side members, and against the base plate of the joint bar. The track bolts will then be inserted and the nuts thereon screwed up so as to draw toward each other the upper 120 margins of the side members 7 and 8. By the clamping action of the said bolts, the wedge member will be held or firmly gripped between the rails and the surfaces of the joint bar in contact with said wedge 125 member, so that said wedge member will be held from moving endwise or becoming loosened through jarring action, independently of the holding effect of the spike 19. Moreover, by the clamping action of said 130

track bolts, any spreading apart of the side members 7 and 8 under the wedging action of the wedge member will be prevented, so that the meeting ends of the rails will be rigidly and firmly clamped in place and there will be no looseness in the joint by reason of the elasticity of the metal of the side members themselves, or of the metal at the parts by which the said side members are joined to the side margins of the base-plate. It is to be understood, however, that aside from the feature of the track bolts, arranged in co-operation with the wedge piece to afford rigid connection of the rails with the joint bar, important advantages are gained by the use of the wedge-piece made as described, namely, with integrally connected base and upright members, for the reason that, when the wedge-piece is driven into place, it serves to force or press the base flanges of the rails downwardly against the base plate and at the same time to press or clamp the webs of the rails against the opposing side member 7, while at the same time, the wedge-piece itself, by reason of the rigid and unyielding connection of its base and upright members, or of its angular cross-sectional form, possesses a considerable degree of longitudinal stiffness or rigidity, and therefore materially aids in holding the ends of the rails in alinement with each other.

As a further improvement, I have provided, in connection with a joint bar or joint plate adapted to be rigidly clamped or secured to the meeting ends of the rails, anchoring means comprising an anchoring member 25 adapted to be buried in the ground, and a tie rod 26 connecting said anchoring member with the joint bar. As illustrated, the anchoring member 25 consists of a piece of wood, such as one-half of an old tie, and the tie rod 26 is provided with a loop member 27 which extends around the anchoring member, or through which said anchoring member is inserted. As shown, the tie rod is flexibly connected with the loop member by means of interlocked eyes or rings 26^a, 27^a on said parts. For detachably connecting the tie rod 26 with the joint bar, the vertical flange 17, on one end of the base plate 6, is provided with an apertured lug 17^a engaged by a hook 26^b on the adjacent end of the said tie rod.

While an anchoring device made as described may be used for holding the rail joint and rails from being moved or shifted either laterally or endwise, the same is shown in the drawing, as applied for the purpose of holding the joint bar and rails from being shifted endwise in one direction. For this purpose the anchoring member 25 is shown as buried in the ground at some distance horizontally from the adjacent end of the joint bar, and the tie-rod 26 is shown as extending in an inclined direction from the

anchoring member upwardly to its point of connection with the joint bar. An anchoring device thus arranged operates independently of the ties and serves to hold the rails from endwise movement either by the shifting of the entire track or by the shifting of the rails on the ties. Such an anchoring device will be especially applicable in cases where there is a tendency of the rails to creep or move endwise under the action of passing trains on inclines or grades; it being well understood that while trains pass always in one direction on such an incline or grade, the rails tend to creep or move toward the lower end of the grade. When the joint bar is held from endwise movement by an anchoring device made as described, any tendency of the rails to shift or move endwise in the joint bar will be resisted by the contact of the track bolts (which closely fit in the holes in the rail-webs), with the ends of the bolt-holes in the side members 7 and 8. As an additional means of preventing any endwise movement of the rails relatively to the joint bar, the latter may be provided, as shown in Fig. 3, with a stop member or lug 23, made integral with and rising from the base plate 6, and adapted to engage a notch 5^b, formed in the base flange of one of the rails at the meeting ends of the latter. If an anchoring device made as described, be arranged with its anchoring member at one side or the other of the joint bar, it will hold the joint bar and the rails from shifting sidewise under the lateral pressure of the flanges of the wheels on the rails, due to the centrifugal action of trains passing around curves at high speed.

It is to be understood that the devices illustrated may be variously modified with respect to details of construction without departure from the spirit of my invention and I do not, therefore, desire to be limited to the specific features of structure and design illustrated except so far as the same may be pointed out in the appended claims as constituting parts of my invention.

I claim as my invention:

1. In a rail-joint, the combination of a joint-bar consisting of a horizontal base-plate for supporting the rail-ends, and integral, longitudinal side members extending inwardly over the base-flanges of the rails and upwardly at the sides of the rail-webs, one of said side members conforming on its inner surface to the shape of the rails and the other of said side members having its inner surface spaced from the webs and base-flanges of the rails and being longitudinally inclined on its inwardly and downwardly facing surfaces, each of said side members being provided with elongated bolt holes adapted to register with the bolt holes in the rail-webs, a tapered wedge-piece consisting of integrally united base and upright

- members shaped on their inner surfaces to conform to the base-flanges and webs of the rails and inclined on their outwardly and upwardly facing surfaces, said wedge-piece 5 being provided with elongated bolt holes adapted to register with the bolt holes in the rail webs and the side members of the joint bar, a transverse arm on the larger end of said wedge-piece and extending outwardly 10 therefrom and in position for contact with said base-plate, said arm being provided with a spike-hole, and track bolts inserted through the bolt-holes in the side members, the rail-webs, and the wedge-piece.
- 15 2. In a rail joint, the combination of a joint-bar, consisting of a horizontal base-plate and integral, longitudinal side members extending from said base-plate, inwardly over the base-flanges of the rails and 20 upwardly at the sides of the rail-webs, said side members being substantially shorter than the length of the base-plate, one of said side members conforming on its inwardly and downwardly facing surfaces to 25 the shape of the rails and the other having its inner and downwardly facing surfaces

spaced from the surfaces of the rails, said side members being provided with bolt holes adapted to register with the bolt holes of the rail webs, a longitudinally inclined wedge-piece having integrally united base and upright members, said members being inclined on their outwardly and upwardly facing surfaces, said wedge piece being provided with elongated bolt holes adapted to register with the bolt holes of the rail webs and the joint bar, a transverse arm on the larger end of the wedge-piece, extending outwardly therefrom with its lower surface in position for contact with the top surface of the base-plate, said arm being provided with a spike-hole, and track bolts inserted through the bolt holes of said side members, the rail-webs, and the wedge-piece.

In testimony, that I claim the foregoing 45 as my invention I affix my signature in the presence of two witnesses, this 11th day of February, A. D. 1913.

CHARLES CALVERT LAMB.
